UNITED STATES PATENT OFFICE.

JOSEPH G. HESTER, OF WASHINGTON, DISTRICT OF COLUMBIA, ASSIGNOR
OF FORTY-FIVE ONE-HUNDREDTHS TO JULIUS LANSBURG, OF SAME
PLACE.

PEN-HOLDER.

SPECIFICATION forming part of Letters Patent No. 246,769, dated September 6, 1881.

Application filed June 22, 1881. (No model.)

To all whom it may concern:

Be it known that I, JOSEPH GOODMAN HESTER, a citizen of the United States, residing at Washington city, District of Columbia, have 5 invented new and useful Improvements in Pen-Holders, of which the following is a specification.

Pen-holders as ordinarily constructed are provided with a pen-slot at one end, arranged 10 between two immovable surfaces or cylinders, and the removal of the pen therefrom when necessary, by reason of the same becoming worn or broken, is rendered exceedingly difficult when it has become cemented in place by 15 corrosion. To avoid this difficulty it has been suggested to arrange within the barrel of the holder proper a sliding plug, between which and the barrel the pen is held. This sliding plug has been arranged to operate automatically 20 to eject the pen by the force of a spring arranged at its upper end, and which is compressed when the plug is in its normal position, and so held by a short button or pin locking in a bayonet-slot in the barrel of the holder; and it has also been arranged without a 25 spring and operated positively by a pin or button projecting through a straight slot in the barrel of the holder. I have discovered that these methods only partially overcome 30 the difficulties, because where spring-pressure is used it is difficult to preserve the proper amount of power, the necessity for which increases as the pen becomes more firmly attached to the parts by long use, corrosion, &c., 35 and because the continued confinement of the spring and the ordinary crystallization of the metal tend to rob it of its elastic force; and where the positive action is provided for in the sliding block with projecting pin or button, the force is applied to such pin or button, 40 which must of necessity be small and arranged at one side, and hence it is difficult of operation.

The object of my invention is to overcome 45 all the disadvantages named and provide a pen-holder with an ejector which shall be positive in its action and unlikely to become broken or disarranged; and with these ends in view my invention consists of a pen-holder 50 bored or open centrally from end to end, and

provided with an axially-arranged ejector longer than the pen-holder, and having one end adapted to confine a pen between itself and the inside of the barrel of the holder, the opposite end projecting beyond the upper end 55 of the holder a sufficient distance to enable a longitudinal movement to be given to a suitable degree to eject the pen, as will be herein-after and in detail explained.

My invention further consists in the special 60 details of construction of the several parts, as hereinafter set forth and specifically claimed.

In order that those skilled may fully understand the construction and operation of my improved pen-holder, I will proceed to describe 65 the same, referring by letters to the accompanying drawings, forming part of this specification, and in which—

Figure 1 is a central longitudinal section of a pen-holder embodying my invention. Fig. 70 2 is a similar view with a spring attached to return the ejector to its normal position after the ejection of the pen; Fig. 3, a similar view of a modification of my invention, showing the spring arranged internally and the head of 75 the ejector provided with radial projections to limit the return movement of the same. Fig. 4 is a cross-section taken at the line *x x* of Fig. 1; Fig. 5, a partial longitudinal section with the pen held in position for use; Fig. 6, a similar view with the ejector forced out and the pen discharged, and Fig. 7 an end view of the radially-enlarged ejector-head in the modified form shown at Fig. 3.

Similar letters indicate like parts in the several figures.

A represents the handle of the pen-holder, which may be made of wood, hard rubber, or other suitable material, preferably tapering in form, though any other desired form may be 90 adopted. This holder is made hollow, or formed with an axial bore from end to end, adapted to receive a longitudinally-reciprocating ejector, *B*, which is provided at its forward end with a head, *C*, the inner end of which is preferably made tapering, and adapted, when in its normal position, to rest against an annular shoulder, *a*, on the interior of the pen-holder. The relative diameters of the pen-holder *A* and 95 head *C* of the ejector are such that sufficient 100

space is left between the surfaces of the two to accommodate and securely hold the pen when placed in position.

The periphery of the head C may be notched 5 or grooved longitudinally, as shown, to form a seat for narrow pens.

The ejector B may fit loosely within the holder A, as shown; or the rod and the axial bore of the holder may be of a near diameter, so that 10 the ejector may be operated and guided through an exact axial line.

The movement of the ejector, both to eject the pen and return the former to its place, may be positive and by hand, as shown at Fig. 15 1; or the pen may be ejected positively by the application of power to the upper extended end of the ejector and the ejector returned by a spring, D. This spring D may be secured in operative position between the upper end of 20 the pen-holder and a nib, b, on the end of the ejector to form an ornamental finish, as shown at Fig. 2; or it may be secured nearer the center by being fastened at one end to the case and confined at the other by a collar, c, secured 25 to the ejector, which collar is slightly tapered and adapted to find its seat within the holder A by wedging.

The upper end of the ejector B may project, as seen at Fig. 1, or it may be concealed by and 30 connected to a short telescopic cap, E, Fig. 3.

The shoulder a, which stops the ejector at the proper point, as seen at Figs. 1 and 2, may be used to control the depth of insertion of the pen, and the return movement of the head C 35 of the ejector limited and determined by one or more short radial arms or flanges, d, (see Fig. 7,) so arranged or disposed as to leave one or more spaces, e, for the reception of different sizes of pens.

40 The ejector B may be of one diameter from its head up, as shown at Figs. 1 and 2. It may be tapered, or it may be stepped and of different diameters, corresponding to different diameters in the bore of the holder, as shown at Fig. 3.

45 The ejector-head C may be perfectly cylindrical throughout its entire length, as shown at Fig. 3; but I prefer to taper the inner end, as shown at Figs. 1, 2, and 6, so that when projected, as shown at Fig. 6, the pen will be free to fall out by its own gravity should the ejector fail to carry it, which is not likely.

In introducing the pen it attaches itself with greater frictional tenacity to the ejector-head C than to the barrel of the holder, and hence

when the former is projected beyond the latter the pen is carried out, and will not remain in contact with the barrel of the holder.

I am aware, as before stated, that means have heretofore been suggested for removing 60 pens; but I am not aware that the ejector has ever before, while arranged axially, extended entirely through and beyond the pen-holder proper, so that the power used to eject the pen may be applied axially and at a point exactly 65 opposite to the point of resistance, and in such manner that an extra amount of power applied will not injure or disarrange the parts; and the gist of my invention rests in this broad idea, 70 the details of my invention resting in the several peculiarities in the arrangement of the spring and the particular form of the ejector-head.

Having described my invention, what I claim as new, and desire to secure by Letters Patent, 75 is—

1. In combination with a pen-holder open or bored centrally from end to end, a reciprocating ejector, B C, adapted to confine the pen at one end and extended at the opposite 80 end beyond the end of the holder, substantially as and for the purpose set forth.

2. In combination with the holder A, bored or open from end to end, and the ejector B C, arranged therein, as described, and adapted 85 to be operated positively, as set forth, to eject the pen, a spring, D, adapted to return the ejector to its normal position.

3. In combination with the pen-holder A and ejector B C, the telescopic cap E, for concealing 90 and protecting the upper end of the ejector, as hereinbefore set forth.

4. The ejector-head C, adapted at its outer end to confine the pen in place against the barrel of the holder, and having its inner end tapered, as described, to insure the releasement 95 of the pen, as hereinbefore set forth.

5. The head C of the ejector, having its outer end formed with one or more radial arms or projections, d, in combination with the end or 100 annular shoulder of the holder A, whereby the return movement of the ejector is limited, substantially as hereinbefore set forth.

In testimony whereof I have hereunto set my hand and seal in the presence of two subscribing witnesses.

JOSEPH G. HESTER. [L. S.]
